ABSTRACT

A blind riveted joint, wherein a row of rivet heads are recessed within a groove provided along a joint connecting two stakes in a side wall of a transit vehicle, has one edge of a cover strip inserted between a lip provided along one side of the groove and a support within the groove. An integral, deformable flange projects from the inner side of the cover strip adjacent its opposite edge, and this flange is forced by external pressure into a slot provided along its corresponding side of the groove. The slot is shaped to deform the flange as the latter is forced therein, thereby firmly anchoring the cover strip across the opening to the groove. The first mentioned cover strip edge portion preferably is separated from the rest of the strip by a scored line to weaken the strip and thus facilitate and localize bending along this line.

BLIND, RIVETED JOINT FOR PANEL MEMBERS

BACKGROUND OF THE INVENTION

In the manufacture of transit vehicles such as buses and rail cars a recent development consists in manufacturing a floor assembly, two side walls assemblies, roof assembly, and front and rear end assemblies individually in separate jigs provided for this purpose. After these assemblies have been individually completed they are assembled with each other to complete the vehicle. Each side wall of the vehicle comprises a skeletal frame structure including upright posts or mullions, which frame structure is sheathed externally with horizontal strakes, usually of extruded aluminum. Edge portions of adjacent strakes are riveted together with the heads of the rivets recessed in a groove provided by the edge formation of the strakes. In the past, these grooves have been either covered by a strip of suitable material, such as stainless steel or aluminum, or filled with suitable material, such as a flowable, hardenable substance. Such prior materials have not been difficult to deface or remove, and therefore have been subject to damage by vandals or pranksters.

SUMMARY OF THE INVENTION

The present invention provides a cover strip for a grooved, riveted joint connecting two panel type members, the rivet heads lying wholly within the groove. The cover strip is pressed into anchored position in the groove by first inserting one edge of the strip into a recess provided along one side of the groove, and then forcing a deformable element projecting inwardly from the other edge of the strip into a slot provided in the strake defining the other side of the groove. The slot is so shaped that when the projecting element is forced therein under external pressure the deformable element is deformed, and thereby anchors the cover strip in position to close the groove and conceal the row of rivet heads therein. The cover strip when thus applied is firmly seated, strong, and rattle free, but can be removed if required by destroying the strip, for example, by severing it lengthwise with a saw or other suitable tool and then removing the two severed parts.

In a modified form of the invention, two divergent, deformable elements are provided on the cover strip instead of one, with two slots to receive them.

BRIEF DESCRIPTION OF THE DRAWINGS

The objectives and advantages of the invention will be apparent from the following description and the accompanying drawings, wherein:

FIG. 1 is a view, partly in transverse section and partly in elevation, showing one edge of the cover strip inserted beneath the lip provided along one edge of the groove, with the free edge of the deformable flange located at the entrance to its slot, ready to be forced home by external pressure.

FIG. 2 is a similar type of view showing the cover strip alone.

FIG. 3 is a similar type of view showing the deformable flange forced by external pressure into its slot and anchored therein by the resultant deformation of the flange.

FIGS. 4, 5 and 6 are respectively similar to FIGS. 1, 2 and 3, but show a modified, double flange, double groove anchoring structure.

DETAILED DESCRIPTION OF THE DRAWINGS

Referring to the form of the invention shown in FIGS. 1 - 3, a pair of generally similar strakes 10 and 11, preferably aluminum extrusions, are joined together in edge-to-edge relation by a row of rivets 12. The strakes comprise outer plate portions 13 and 14, respectively, with inwardly extending support flanges 15 and 16 along adjoining edges thereof. Each support flange has

10 a mounting flange 17 along its inward edge by means of which the strakes may be attached by conventional means, such as rivets, not shown, to support members, also not shown, such as the usual posts or mullions of a transit vehicle side wall frame structure.

15 A first riveting flange 19 extends laterally from an intermediate portion of the support rib 15, and is overlapped by a second riveting flange 20 extending laterally from the support rib 16 of the adjacent stroke 11. These riveting flanges 18 and 19 are joined together by 20 the rivets 12, with the outer surfaces of the strakes defining a substantially common surface, the rivet heads being recessed in a groove 21 provided by inward offsetting of the riveting flanges 19 and 20.

25 A narrow flange 22 extends from the support rib 15 and is spaced from the flange 19 to receive and retain the free edge of the riveting flange 20 between it and the riveting flange 19. A cover strip support rib 23 is provided along the outer side of the riveting flange 20 and is located to just clear the narrow flange 22 30 when the strakes 10 and 11 are assembled as shown in FIGS. 1 and 3. The outer plate portion 13 of the strake 10 has a co-extensive retaining lip 26 along its edge to receive therebeneath a first edge portion of a cover strip 24.

35 The cover strip 24 for covering the groove 21 preferably is of a material corresponding to that of the strakes, and has an inwardly extending, deformable locking flange 28 along its opposite edge. A scored line 29, see FIG. 2, also preferably is provided in the cover strip to lie alongside the support 23 when the cover strip is inserted as shown in FIGS. 1 and 3 to facilitate and localize bending of the cover strip along this line.

40 A transversely curved slot 25 is provided in an inwardly offset, thickened portion 27 provided in the strake 11 along the portion thereof which defines the opposite side of the groove 21 from the lip 22, this slot being shaped to receive and deform the deformable locking flange 28 when the latter is forced therein under external pressure applied to the locking strip as indicated diagrammatically by the roller A in FIG. 1.

45 The outer surface of the thickened portion 27 is offset inwardly from the surface defined by the outer faces of the plate portions 13 and 14 of the strakes 10 and 11 a selected distance relative to the thickness of the cover strip 24 so as to bring the outer surface of the cover strip, when set thereon as shown in FIG. 3, into desired relation with the outer surface of the strakes.

OPERATION OF THE FORM OF THE INVENTION SHOWN IN FIGS. 1 - 3

50 Assuming that the strakes 10 and 11 are fitted together as shown in FIGS. 1 and 3, and the rivets 12 are inserted and set as shown in these figures, for inserting the cover strip 24, a first edge portion 24a thereof, see FIG. 2, is inserted as shown in FIG. 1 between the support flange 23 and the retaining lip 26, thereby positioning the free edge of the deformable locking flange

28 at the entrance to the slot 25. Pressure is then applied to the external side of the cover strip 24 over the locking flange 28 as by means of suitable or well known mechanism such as, for example, a presser roller A, see FIG. 1, the pressure being sufficient to force the locking flange 28 its full depth into the slot 25. This action deforms the flange 28 as shown in FIG. 3 thereby to firmly lock the cover strip in seated relation across the entrance to the groove 21, thereby covering and concealing the rivet heads. It will be obvious to one familiar with this type of operation that by varying the thickness of the cover strip 24, other than the edge portion 23 which is inserted beneath the lip 26, the external surface of the cover strip can be made either recessed, flush with, or projecting above the outer surface defined by the strakes 10 and 11.

MODIFIED FORM OF THE INVENTION SHOWN IN FIGS. 4 - 6

In the modified form of the invention shown in FIGS. 4 - 6, the structure of the strakes and cover strip are generally the same as that shown in FIGS. 1 - 3, with the exception of the deformable locking flange and its slot. Corresponding parts of the form of the invention shown in FIGS. 4 - 6 are, therefore, designated by the same reference numerals as those employed in FIGS. 1 - 3 with the prime (') added.

In FIGS. 4 - 6, instead of a single deformable locking flange and slot, a pair of deformable locking flanges 30 and 31 are provided to extend divergently inwardly from the inner surface of the cover strip 24'. A pair of diverging slots 32 and 33 are also provided in a thickened strake portion 27', and diverge at a greater angle than that of the locking flanges 30 and 31.

The entrance to the diverging slots 32 and 33 is of a width to receive the free edges of the locking flanges 30 and 31 therein when the cover strip 24' is applied as shown in FIG. 1. When the cover strip 24' is pressed home by suitable pressure applied to the exterior of the cover strip 24', the flanges 30 and 31 are forced apart and into their respective slots 32 and 33 as shown in FIG. 6, thereby firmly locking the cover strip in seated position.

The invention provides a simple, inexpensive cover strip for covering the rivet head receiving groove between adjacent riveted strakes of a transit type vehicle, and in normal use endures for the life of the vehicle.

Having thus described my invention, what is claimed as new and useful and desired to be secured by U.S. letters Patent is:

1. A blind, riveted joint wherin a row of rivet heads are recessed in a groove provided along a joint connecting two strakes in a sidewall of a transit vehicle, said joint comprising:

a cover strip of a width to span such groove, strake material defining a recess along one side of such groove for receiving and retaining one edge of the cover strip,

strake material defining an outwardly open, inwardly inclined slot along the other side of such groove, a deformable locking element integral with and extending inwardly from the inward side of the cover strip, said deformable element being so shaped and located that with said one edge of the cover strip in such recess, the free end of the locking element is positioned to enter such slot upon the application of external pressure to the cover strip over the

locking element, and in a direction substantially normal to the outer surfaces of the strakes, the strake material defining such slot being so shaped as to deform the locking flange against withdrawal when the latter is forced into the slot, and means for forcing the deformable element into such slot.

2. A blind, riveted joint as claimed in claim 1 wherein such recess for receiving the first edge of the cover strip is defined by a lip extending from an edge of strake material defining one side of the groove, and a support element extending from strake material defining the bottom of the groove and spaced inwardly from said lip by the thickness of said first edge of the cover strip.

3. A blind, riveted joint as claimed in claim 2 wherein a scored line is provided lengthwise of the cover strip to lie alongside said support element when the first edge of the cover strip is inserted between said lip and said support.

4. A blind, riveted joint as claimed in claim 1 wherein the deformable element comprises a narrow rib.

5. A blind, riveted joint as claimed in claim 4 wherein the cover strip is an aluminum extrusion.

6. A blind, riveted joint as claimed in claim 1 wherein the deformable element comprises a pair of divergent, narrow ribs, and a pair of slots are provided and located so that each of such slots receives one of the ribs.

7. A blind, riveted joint wherin a row of rivet heads are recessed in a groove provided along a joint connecting two strakes in the side wall of a transit vehicle, said joint comprising:

a cover strip of a width to span such groove, a lip extending along one side of such groove for receiving one edge of the cover strip therebeneath, a strake element shaped to support the other edge of the cover strip and having an outwardly open, inwardly inclined slot therein,

a deformable locking element integral with and extending inwardly from an opposite edge portion of the cover strip, said locking element being of a size, and so shaped and located, that with said one edge of the cover strip inserted beneath said lip, the locking element will enter such slot upon the application of required external pressure to the cover strip over the deformable element, and in a direction substantially normal to the outer surfaces of the strakes, the strake material defining such slot being shaped to deform the locking element against withdrawal when the locking element is forced into such slot.

8. A blind, riveted joint as defined in claim 7 wherein a support is provided within the groove in position to support the inner side of said one edge of the cover strip in contact with the inner side of said lip.

9. A blind, riveted joint as defined in claim 8 wherein said support comprises a rib integral with a strake element comprising the bottom of such groove.

10. A blind, riveted joint for joining two adjacent panel members in edge-to-edge relation, each panel member having a laterally extending riveting flange formed integrally therewith, the riveting flanges being in relatively superposed, contacting relation with each other and spaced inwardly from a common outer surface defined by the panel members to form a groove therein with one of the riveting flanges comprising the bottom of such groove.

a row of rivets joining the overlapping riveting flanges, the heads of the rivets being recessed in such groove,
 a cover strip retaining lip extending into one side of the groove along an outer surface portion of one of the panel members,
 a cover strip of a width to span such groove with one edge of the cover strip inserted beneath said lip,
 a deformable anchoring element integral with, and projecting inwardly from an area adjacent the 10

other edge of the cover strip, and a cover strip support element integral with one of the panel members and extending along the other side of such groove, said support element having a slot therein of a size, and so positioned, as to receive the deformable anchoring element therein, the sides of such slot being formed to deform said anchoring element against withdrawal when the anchoring element is forcibly inserted into such slot.
